UNITED STATES PATENT OFFICE.

HENRY F. A. KLEINSCHMIDT, OF JOHNSTOWN, PENNSYLVANIA, ASSIGNOR TO THE LORAIN STEEL COMPANY, OF JOHNSTOWN, PENNSYLVANIA, A CORPORATION OF PENNSYLVANIA.

RAIL-JOINT.

1,111,594.

Specification of Letters Patent. Patented Sept. 22, 1914.

Application filed May 14, 1913. Serial No. 767,517.

To all whom it may concern:

Be it known that I, HENRY F. A. KLEIN SCHMIDT, a citizen of the United States, residing at Johnstown, in the county of Cambria and State of Pennsylvania, have invented a new and useful Rail-Joint, of which the following is a specification.

My invention relates to the construction and arrangement of rail joints, and more particularly the rail joints of electric rail-ways in which the splice bars used in mechanically connecting the abutting ends of adjoining rails also serve to form electrical connectors or bonds for the adjoining rail ends.

One object of this invention is to provide a rail joint having novel means whereby the ends of the rails are mechanically and electrically connected and relative movement thereof is overcome and prevented.

Another object of my invention is to provide a rail joint having a welded splice bar which when applied for use is adapted to form a support for the rail heads.

A further object of the invention is to provide a rail joint of novel construction having improved means whereby the ends of rails of varying sizes are secured together in place and the rail heads adjacent to the joints therebetween are supported by the splice bars.

Still further objects of the invention will become apparent as the invention is more fully described in the specification and specifically pointed out in the appended claims.

Referring to the accompanying drawings forming part of this specification, Figure 1 is a longitudinal side elevation showing a rail joint having the splice bars applied for use thereto in connecting the adjacent ends of adjoining rails in accordance with my invention. Fig. 2 is a transverse section of the rail joint of Fig. 1 showing the rail joint with the splice bar as secured thereto prior to bringing the splice bar in position to support the rail head. Fig. 3 is a similar transverse section showing the splice bar as secured in place in forming the rail joint.

In the accompanying drawings, the numeral 2 designates the web of a girder rail having an integrally formed head 3 and base flanges 4.

Secured to the web of the rail is a splice bar 5 which is welded to the rail web to fasten the adjoining ends 6 and 7 of two

rails together in forming a joint therebetween.

The splice bar 5 is provided with a flange 8 on its upper edge in the middle of its length, this flange preferably being somewhat shorter than the overall length of the lower portion 9 of the splice bar and a slot or groove 10 is provided in the middle of the length of the flange on the splice bar so as to in effect provide two flanges 8 on each splice bar.

The splice bar shown is formed so that when welded to the rail the flange portions 8 thereof are bent outwardly as shown in Fig. 2, in such manner as to be clear of the underside of the rail head 3.

After the welding operation by which the ends of the rails 6 and 7 are secured to the splice bar 5 the electrical welding apparatus used in welding the splice bar to the rails is placed in position to contact with the portion of the flange 8 engaging with the head of one of the rails, and electric current is then supplied through the terminals of the welding apparatus to heat the flange 8 of the splice bar. When the flange becomes heated so as to be readily bent, pressure is applied thereto so as to force the flange 8 in tight engagement with the adjacent under surface of the rail head 3 so that the flange of the splice bar serves to form a support for the rail head 3.

The flange portion 8 contacting with the other rail head 3 is then heated and forced into position in a similar manner so as to tightly engage with and support the underside of the other rail.

The insertion of such short pieces of rail is of frequent occurrence, oftentimes being made to repair tracks in which the end of a rail has become broken or otherwise damaged and in which the damaged end is severed from the rail, and the new piece of rail substituted therefor.

It should be noted that the lowermost edge of the splice bar does not engage with the upper surface of the bottom flange of the rails, so that the weld is utilized to transmit pressure or forces applied in a downward direction through the supported rail head to the web of the rails.

The advantages of my invention will be apparent to those skilled in the art. By means of my improved rail joint construction the splice bars are welded to fasten the

rail ends together and are then forced into and held in tight engagement with the rail head so as to form a rail support which materially strengthens the rail head.

5. The transverse slot in the splice bar permits of rails of varying cross section to be secured together and have the rail heads supported by the splice bars against vertical displacement relative to the rail web in this 10 manner reinforcing the rail heads at the joints or weakest portion thereof and preventing bending of the rail head.

Modifications in the construction and arrangement of the parts may be made with 15 out departing from my invention as defined in the claims.

I claim:—

1. In a rail joint, a splice bar fastened to the abutting ends of adjoining rail sections 20 and having a flange engaging the under side of the rail heads, said flange being bent into supporting engagement with the rail heads after securing the splice bar to the rails.
25. 2. In a rail joint, a splice bar fastened to the abutting ends of adjoining rail sections and having a sectional flange engaging the under side of the rail heads, said flange section being bent into supporting engagement 30 with the rail heads after securing the splice bar to the rails.
3. In a rail joint, a splice bar welded to the abutting ends of adjoining rail sections and having a flange engaging the under side 35 of the rail heads, said flange being bent into supporting engagement with the rail heads after securing the splice bar to the rails.
4. In a rail joint, a splice bar welded to the abutting ends of adjoining rail sections 40 and having a sectional flange engaging the under side of the rail heads, said flange sec-

tion being bent into supporting engagement with the rail heads after securing the splice 45 bar to the rails.

5. In a rail joint, a splice bar welded to the abutting ends of the webs of adjoining rail sections and having a flange engaging the under side of the rail heads, said flange 50 being bent into supporting engagement with the rail heads after welding the splice bar to the web of the rails.

6. In a rail joint, a splice bar welded to the abutting ends of the webs of adjoining rail sections and having a sectional flange 55 engaging the under side of the rail heads, said flange section being bent into supporting engagement with the rail heads after welding the splice bar to the web of the 60 rails.

7. In a rail joint, a splice bar fastened to the abutting ends of adjoining rail sections and having a flange on one edge intermediate of the ends of the bar engaging the 65 under side of the rail heads, said flange being bent into supporting engagement with the rail heads after securing the splice bar to the rails.

8. In a rail joint, a splice bar fastened to 70 the abutting ends of adjoining rail sections and having a sectional flange on one edge intermediate of the ends of the bar engaging the under side of the rail heads, said flange section being bent into supporting engagement 75 with the rail heads after securing the splice bar to the rails.

In testimony whereof, I have hereunto set my hand.

HENRY F. A. KLEINSCHMIDT.
